No. 32,809.

Patented June 12, 1900.

L. HORNBERGER.

CLOCK CASE OR SIMILAR ARTICLE.

(Application filed May 18, 1900.)

UNITED STATES PATENT OFFICE.

LOUIS HORNBERGER, OF NEW YORK, N. Y.

DESIGN FOR A CLOCK-CASE OR SIMILAR ARTICLE.

SPECIFICATION forming part of Design No. 32,809, dated June 12, 1900.

Application filed May 18, 1900. Serial No. 17,175. Term of patent 7 years.

To all whom it may concern:

Be it known that I, LOUIS HORNBERGER, a citizen of the United States, residing at New York, in the county and State of New York, 5 have invented and produced a new and original Design for Clock-Cases or Similar Articles, of which the following is a specification, reference being had to the accompanying drawings, forming a part thereof.

10 Figure 1 is a front elevation of a clock-case, showing my new design. Fig. 2 is an elevation showing the right-hand side. Fig. 3 is an elevation showing the left-hand side.

As shown in the drawings, the leading or material feature of my design consists of the bust figure of a cupid or nude boy 1, with one hand elevated to the ear as in the act of hearing, as represented at 2, said figure surmounting the circular face-field 3 of a body portion 4 and being backed and surrounded by foliates and foliated scrolls and minute scrolls and foliate ornaments comprised in the general ornamentation of the case, as represented at 5, the front and sides and base of the body 4 beneath the face-field 3 being similarly ornamented with foliates and foliated scrolls, as represented at 6, the whole having a general scroll or curved outline and roccoco ornamentation.

30 The top portion, consisting of the figure "1" and its background, rises in its scroll or curved outline to an apex or point 7. The figure "1" has the right arm 8 extended, with the hand resting upon a projecting scroll-mount, as at 9, while the left arm 10 is elevated and the hand is extended at the ear, and a wing 11 shows at the right-hand side against a field 12, inclosed by a major scroll 13, forming the right-hand side of the top portion of the case.

40 A similar major scroll 14 forms the left-hand side of the top portion. The major scrolls 13 and 14 are surrounded by divergently-extending minute scrolls and foliated ornaments, as at 15, and said major scrolls are surmounted

45 by an assemblage of intertwined scrolls 16, rising above the head of the figure "1" and forming the apex or top 7, the field beneath said scroll series 16 having a flower representation, as at 17. A foliated scroll 18 ex-

50 tends across the figure "1" beneath the bust and under the right arm, as shown.

The body portion of the case comprises the central circular face-field 3 and has at its respective sides a series of major scrolls 19, extending upwardly from the front corners of 55 the base of the body beneath the face-field rearwardly and forwardly and terminating just beneath the top portion hereinabove described. At each side said major-scroll series 19 are emphasized by minor foliated 60 scrolls and foliate ornaments, as at 20. Foliated scrolls, as at 21, spring from the base of the body portion at the front upwardly and around the face-field 3, and between said foliated scrolls 21 and the said major scrolls 19 65 and across the top of the face-field 3 are interspersed flower representations, as at 22. The face of the base of the body portion beneath the face-field 3 has centrally a shield or escutcheon 23, surrounded by scroll and 70 foliate ornaments and foliated scrolls, as at 24. The corners of the base at the front and rear are extended outwardly as a continuation of the scroll ornamentation, as represented at 25, and these base-corners are additionally ornamented by foliated scrolls, as 75 at 26. The body has its outer margin defined by varied scroll or curved lines, as shown.

A distinctive feature of my design is the bold and pronounced relief of all the parts 80 thereof and its general roccoco characteristics with the scroll and foliate ornaments and foliates and foliated scrolls and flower representations, in connection with the bust figure of a cupid or nude boy in the act of 85 hearing.

It is apparent that this design is also applicable to calendar-cases and other similar articles.

Having described my invention, what I 90 claim as new, and desire to secure by Letters Patent, is—

The design for a clock-casing or similar article, substantially as herein shown and described.

In testimony whereof I have signed my name in the presence of the subscribing witnesses.

LOUIS HORNBERGER.
